UNITED STATES PATENT OFFICE.

JOHN WANAT, OF PITTSBURGH, PENNSYLVANIA.

TROLLEY.

1,257,556.

Specification of Letters Patent. Patented Feb. 26, 1918.

Application filed April 30, 1917. Serial No. 165,526.

To all whom it may concern:

Be it known that I, JOHN WANAT, a subject of the Czar of Russia, residing at Pittsburgh, in the county of Allegheny and State 5 of Pennsylvania, have invented certain new and useful Improvements in Trolleys, of which the following is a specification.

This invention relates to electric propulsion and has special reference to a trolley 10 for street cars and the like.

One important object of the invention is to improve and simplify the general construction of devices of this character.

A second important object of the invention 15 is to provide an improved form of trolley which is so arranged as to follow the curvature of a trolley wire or third rail without danger of jumping off of such wire or third rail as frequently happens with the 20 ordinary form of trolley.

A third important object of the invention 25 is to provide an improved form of trolley which is so arranged as to yield slightly in a vertical plane about a point whereby vertical variation in the position of the wire or third rail may be accommodated.

With the above and other objects in view, as will be hereinafter apparent the invention 30 consists in general of certain novel details of construction and combinations of parts hereinafter fully described, illustrated in the accompanying drawings, and specifically claimed.

In the accompanying drawings, like characters of reference indicate like parts in the several views, and:—

Figure 1 is a plan view of a trolley constructed in accordance with this invention and showing a portion of the trolley pole 40 and harp.

Fig. 2 is a side elevation thereof.

Fig. 3 is a section on the line 3—3 of Fig. 1.

Fig. 4 is a section on the line 4—4 of Fig. 1.

Fig. 5 is a view similar to Fig. 1 and showing the positions assumed by the trolley wheels in passing around the wire on the curve.

Fig. 6 is a section on the line 6—6 of Fig. 5.

Fig. 7 is a section on the line 7—7 of Fig. 5.

Fig. 8 is a section on the line 8—8 of Fig. 7.

In carrying out the objects of this invention there is provided a frame bar 10 having a fork 11 at each end. Between the arms of each of these forks extends a shaft 12 the central portion of which is larger 60 than the end portions and forms a journal 13 for a grooved trolley wheel 14 of the ordinary type. Between the arms of each fork and on the smaller portions of the shaft 12 are mounted sleeves 15 the exterior diameters of which equal the diameters of the portions 13 so that when in position a journal of uniform diameter is formed by the portion 13 and sleeves 15 of each shaft. These sleeves moreover 70 have at their ends flanges 16 and wound around each sleeve and bearing at one end against the flange of that sleeve and at the other end against the trolley wheel is a coil spring 17.

It will now be noted that these coil springs normally hold the wheels 14 centrally of the forks and that when in this position the wheels, in their rotation, frictionally rotate the springs 17 while at the same time the sleeves 15 are frictionally rotated by these springs. By reason of this construction wear of the wheel 14 or springs 17 is eliminated. Moreover upon movement of a wheel 14 to one side or the other as 85 shown in Fig. 5 the wheel itself passes on the rotating sleeve so that at no time do the springs rub against either wheel or sleeve in their rotation. Furthermore, upon inspection of Fig. 5 it will be seen that 90 movement of a wheel 14 to one side or the other compresses one of the springs 17 thus permitting the wheel to take such position as to remain on the wire while at the same time the benefits of a double wheel trolley 95 are assured.

In Fig. 5 the wire is indicated at 18 and the stay or brace wire as used on curves, indicated at 19. It will be obvious, however, that a third rail or any other form of rail 100 or wire may be used in connection therewith.

In order to support the frame bar 10 there is provided on the top of the trolley pole 20 a harp in the form of a fork 21 and extending between the arms of this harp is a built 105 up shaft which consists of a section 22 extending from one arm to the other and arcuately channel or trough-shaped. Fitted in the section 22 adjacent each end is a section 23 which is divided longitudinally into two 110

portions one of which has a radius equal to the interior of the section 22 while the other has a radius equal to the exterior of said section 22 whereby when the parts are assembled the shaft is in the form of a complete cylinder. The ends of this built up shaft are fixed in the arms of the harp 21 between said screws 24 while the portions 23 are spaced apart at their inner ends so that the trough sections 22 may pass through an arcuate slot 25 in the frame bar 10. It will be observed from an inspection of Fig. 3 that the slot 25 has a greater arcuate length than the section 22 and by reason of this a slight or limited tilting movement of the frame bar 10 is permitted about the axis of the shaft which is built up of the sections 22 and 23. By reason of this construction the angle between the frame bar 10 and the harp 21 is always substantially the same so that as the trolley pole is raised up the frame bar 10 will be nearly horizontal thus enabling both wheels 14 to effect contact at substantially the same time with the wire 18. It will be obvious that the trolley is used as an ordinary trolley and that by reason of the yielding of the wheels contact is always maintained between the wire 18 and the wheels with practically no danger of the trolley jumping since to effect such jumping both wheels would have to become displaced. There has thus been provided a simple and efficient device of the kind described and for the purpose specified. It is obvious that many minor changes may be made in the form and construction of the invention without departing from the material principles thereof. It is not therefore desired to confine the invention to the exact form herein shown and described but it is wished to include all such as properly come within the scope claimed.

Copies of this patent may be obtained for five cents each, by addressing the "Commissioner of Patents, Washington, D. C."

Having thus described the invention what is claimed as new, is:—

1. In a trolley for cars and the like, a frame bar having a fork at each end, shafts each extending between the arms of a respective fork and having an enlarged central portion, wheels each mounted to revolve normally on the enlarged portion of a respective shaft, independent sleeves revolubly mounted on the ends of said shafts and having an exterior diameter equal to the diameter of the central shaft portions, collars on the outer ends of the sleeves, springs coiled around the sleeves and bearing against the collars and wheels to hold the wheels yieldably in central position on the forks, and means to connect the frame bar tiltably to a trolley pole. 60

2. In a trolley for cars and the like, a frame bar having a fork at each end, trolley wheels each journaled between the arms of a respective fork, means to hold the wheels yieldably in the centers of said forks, a trolley pole having a harp at its upper end, a shaft extending from arm to arm of said fork and fixed thereon and consisting of a section extending between said arms and arcuately trough shape in cross section and a pair of spaced sections each having a portion filling one end of the first section and a second portion concentric with the first section whereby to form completely cylindrical ends, said bar having an arcuate opening therein receiving the center of the arcuate section, said opening being of greater arcuate length than the section whereby to rock slightly thereon. 75

In testimony whereof I affix my signature. 80
JOHN WANAT.
